US0D1071670S

(12) **United States Design Patent** (10) Patent No.: **US D1,071,670 S**
(45) Date of Patent: ** Apr. 22, 2025

(54) **JUG WITH LID**

(71) Applicant: **Igloo Products Corp.**, Katy, TX (US)

(72) Inventors: **John Maldonado**, Katy, TX (US);
James Duke, Katy, TX (US); **James McKenrick**, Katy, TX (US); **Robert Allan Ross**, Golden, CO (US); **Haley Bodziak**, Katy, TX (US); **Jeff Diamond**, Torrance, CA (US)

(73) Assignee: **Igloo Products Corp.**, Katy, TX (US)

(**) Term: **15 Years**

(21) Appl. No.: **29/869,789**

(22) Filed: **Jan. 9, 2023**

(51) LOC (15) Cl. **07-01**

(52) U.S. Cl.

USPC **D7/510**; D7/511; D7/608

(58) **Field of Classification Search**

CLAIM

The ornamental design for a jug with lid, as shown and described.

DESCRIPTION

FIG. 1 is a top perspective view of a jug with lid, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the jug with lid that form no part of the claimed design.

1 Claim, 8 Drawing Sheets
